ATTORNEYS.

UNITED STATES PATENT OFFICE.

CHARLES H. TERRY, OF CINCINNATI, OHIO.

COLLAPSIBLE CORE.

Application filed December 24, 1925. Serial No. 77,455.

My invention relates to devices used in the forming of cavities in molded panels and blocks of plastic material, and is collapsible in order to permit of its withdrawal from the work after the panel or block has been cast.

There have been a number of devices for a similar purpose which have been provided, and it is my object to improve on the 10 structure of the same.

Essentially it is my object to provide a core in the form of hollow plates in which the side walls and edge walls, two of each, are extended and contracted into different 15 relative positions, by the manipulation of a single element which extends out through both open ends of the core. It is also my object more generally to provide a structure in which all four walls are individually controllable, as well as jointly controllable, and in which the operating element extends lengthwise through the whole device with interspaced means for holding the sections in their desired position, so that 20 without relation to the length of the core, it is operable to supply the required mechanism, and so that it is as simple to withdraw and install. In other mechanisms, such as those which rely on wedging 25 action of some parts on others and which rely on the mere withdrawal of the distending means for collapsing the core, instead of positively collapsing it, there are strict limits in the length possible for the core, 30 and it is a problem to assure a true parallelism of opposite sides. Also in other mechanisms, it is not possible, so far as I am advised, to provide for side and edge pieces which are so operated by a central length- 35 wise member as to permit any one of the pieces to be given an additional adjustment by holding the lengthwise adjustable member still, and moving the piece to be adjusted with relation to it.

40 In the drawings:—

Figure 1 is a cross section of my device on the line 1—1 of Figure 3.

Figure 2 is a section taken longitudinally on the line 2—2 in Figure 4 showing the 50 edge sections contracted.

Figure 3 is a like view showing the edge sections extended.

Figure 4, Figure 5, Figure 6 and Figure 7 are detail views showing the several positions of the side wall control cams, Figure

4 being taken along the line 4—4 in Figure 8.

Figure 8 is a view similar to Figure 1 showing in cross section a contracted condition of the device.

60

The structure may take a number of different shapes, of which I have shown merely a much flattened octagon. In forming this particular design, the side walls of the structure are formed of metal plates having 65 bodies 1 and 2, and divergent terminal flanges 3, 3 and 4, 4. Held movably within the structure, which may be of any desired length within practical limits, are edge blocks 5 and 6, which are shaped so that 70 when extended and located between the flanges of the side plates, the faces of the blocks will fill out the lateral edges, forming in the device shown an octagonal shaped device, as will be evident from an examination 75 of Figure 1 and Figure 8.

Preferably I may provide a flexible covering for the side edges of the collapsible core device, by employing pieces of canvas as at 7, which are secured along their edges 80 to the blocks and extend out over the flanges of the side plates, and riveted into position by rivets 8 or any other desired means. As shown there are two folds of the canvas, one attached to one flange and one to the 85 other. The position of the canvas will be of covering the joint, and protecting it from influx of plaster, and the canvas is not required when the mold is used within a core of cardboard, or other substance. Hence 90 I have shown it at but one edge in the several views noted, although in any one device, both edges will be protected by canvas, or neither of them.

A hollow bar 9 extends lengthwise 95 through the middle of the form, supported as will be described, and on this bar at a plurality of locations, in a mold of any length, will be supporting arms 10 pivoted on the bar, and pivoted to the edge 100 blocks, as by the screws 11, shown in the drawing.

When the central bar is moved lengthwise, the two blocks are spread as shown in Figures 2 and 3, in which the arms are in 105 block spreading position in Figure 3, thus pushing the blocks out into a position of filling the gaps left between the flanges of the side plates.

Mounted in a series along each of the side 110

plates on the inside thereof are angle plates 12, on which are pivoted the cams 13. These cams in addition to being pivoted as at 14 to the angle plates are connected together in pairs by a pin 15, which passes through the lengthwise operating bar, said bar having a suitable slotted aperture 16, in two of its walls for this purpose.

As a result, when the bar is moved lengthwise of the core, it will first slide from the position shown in Figure 7 to the position of Figure 6, thus bringing the end of the two slots against the connecting pin of the cams, for as many pairs of cams as are employed depending upon the length of the device.

As the bar is continued in its movement it rocks the cams, in the same direction at each side, to the position shown in Figure 7, which thrusts out the side walls of the device and holds them in braced outer position. The bar is then thrust further, as at Figure 4, which is permitted by the slotted engagement with the connecting pin.

The slot is used because of the fact that the movement necessary to swing the edge block arms is greater than that required to move the cams to extended position.

In removal of the core the operations are reversed, usually by driving the lengthwise bar from the other end of the core in the opposite direction to the extending movement. The rocking of the cams results in the pivot centers thereof being drawn toward the center of the common pivot pin, in the lengthwise bar, with the result of pulling inwardly on the angle iron brackets that are secured to the side walls and on which the cams are pivoted. Also the arms connected to the edge blocks are brought to a small angle which pulls inwardly on the edge blocks, this action taking place before the side sections are contracted inwardly due to the slots in the lengthwise bar.

When the core has been expanded, and any one section thereof is not properly lined up with the others, due to loose connections or what not, the operator by tapping inwardly from either end of the device can cause the section to move of itself with relation to the lengthwise bar, thus bringing about a change in position of the particular section in question, without changing the position of the lengthwise bar or the other sections.

The device is simple and quickly and effectively operable, with positive movement of parts at all points, and no chance of becoming jammed, and failing to operate. In its essence a single lengthwise operating member extends the side plates and edges of a collapsible core, of which the shape is not essential, nor the relative sizes of the

side plates and edge blocks, since the blocks might be of larger area than the side plates if desired, or vice versa. Neither are the divergent flanges on the side plates a necessity in my construction.

The advantages of the divergent flanges are that they permit of a closed hollow core member being formed in various positions of distension, a factor not ordinarily of importance in the molding of plastic substances in the manner for which my invention is adapted.

Having thus described my invention, what I claim as new and desire to secure by Letters Patent, is:

1. A collapsible core device having side plates and edge blocks, a lengthwise movable member within said core, and means within the core and operable by the lengthwise movable member for positively thrusting outwardly from the center of the core, and drawing inwardly from expanded position both the edge blocks and the side plates, said means comprising arms connected to the lengthwise movable member and the edge blocks, and cams mounted on the side plates and engaged by the lengthwise movable member.

2. A collapsible core device having side plates and edge blocks, means for moving said plates and blocks inwardly from expanded position to reduce the circumference of the core, and flexible members secured to the edge blocks, and extending out across the ends of the side plates to close the joint between blocks and plates.

3. A collapsible core having side portions and edge portions which abut one another at adjoining edges lengthwise of the device when extended, a bar extending longitudinally through the core, means pivoted on the core portions for supporting said bar, said supporting means being arranged with cam edges to abut the core portions on which they are mounted when the bar is moved lengthwise of the device.

4: A collapsible core having side portions and edge portions which abut one another at adjoining edges lengthwise of the device when extended, a bar extending longitudinally through the core, means pivoted on the core portions for supporting said bar, said supporting means being arranged with cam edges to abut the core portions on which they are mounted when the bar is moved lengthwise of the device and arms on the bar, and extending to other portions of the core to extend said portions, when the bar is moved to rock said pivoted supporting means, and to contract said core by moving the portions inwardly upon a movement of the bar in the opposite direction.

CHARLES H. TERRY.
